PAPER CUTTER

Henry R. Mejia, North Kansas City, Mo.

Application March 30, 1951, Serial No. 14,670

Term of patent 14 years

(Cl. D74—1)

To all whom it may concern:

Be it known that I, Henry R. Mejia, a citizen of the United States, residing at route #8, North Kansas City, in the county of Clay and State of Missouri, have invented a new, original, and ornamental Design for a Paper Cutter, of which the following is a specification, reference being had to the accompanying drawing, forming a part thereof, wherein:

Fig. 1 is a perspective view of the paper cutter, showing my new design.

Fig. 2 is an elevational view showing one side thereof.

Fig. 3 is a rear elevational view thereof.

Fig. 4 is an elevational view showing another side thereof.

Fig. 5 is a front, elevational view thereof; and Fig. 6 is a top plan view thereof.

I claim:
The ornamental design for a paper cutter, as shown.

HENRY R. MEJIA.
